UNITED STATES PATENT OFFICE.

HALLIGAN JOHNSON, OF JACKSONVILLE, FLORIDA, ASSIGNOR TO NUDEVICE COMPANY, OF JACKSONVILLE, FLORIDA, A CORPORATION OF FLORIDA.

PASSENGER CAR FOR AMUSEMENT RIDES.

Application filed April 26, 1926. Serial No. 104,664.

My invention relates to cars for Ferris wheels, merry-go-rounds, etc., and has for its main object to provide a car of novel construction which will impart additional pleasure and thrills to the passengers on such rides. These and various other objects and advantages will be readily understood from the following description and from the accompanying drawings of preferred embodiments, but it will be seen that various modifications might be made without departing from the scope of the invention.

In the drawings:

Fig. 1 is a front elevation of my invention, shown as applied to a Ferris wheel.

Fig. 2 is a cross-sectional side elevation of Fig. 1.

Fig. 3 is a fragmentary side elevation of a car, shown as applied to a merry-go-round.

Fig. 4 is a top view of Fig. 1.

Fig. 5 is a cross-sectional top view, taken on line 5—5 on Fig. 1.

Fig. 6 is a cross-sectional top view, taken on line 6—6 on Fig. 3.

Fig. 7 is a fragmentary front view of certain parts, drawn to a larger scale than the rest of the views.

Fig. 8 is a view of the bottom car support.

Referring first to Figs. 1, 2, 4 and 5, in which the car is shown attached to a Ferris wheel, 10 and 11 represent fragments of the revoluble frame of a standard Ferris wheel and 12 one of the car supporting shafts attached in the circumference of such a wheel.

In the present invention, the shaft 12 is rigidly attached between the frames 10 and 11 and a yoke, consisting of two bearings 13 and 14 having hangers 15 and 16 supporting a cross-member 17, is suspended from this shaft and free to rotate thereon. A vertical bearing 18 is provided in this cross-member and a vertical shaft 19 is journaled in this bearing. To the upper end of the shaft 19, a bevel gear 20 is rigidly attached which is driven by a bevel gear 21 rigidly attached to the shaft 12.

The passenger car, which is indicated in its entirety by the numeral 22, is suspended on the vertical shaft 19 by means of the support 23 rigidly attached under the car floor 24. This support, which is shown in detail in Fig. 8, consists of a body part 25, having a square hole 26 in its center, and four arms 27. The lower end of the shaft 19 is provided with a squared portion 28, which fits

loosely into the hole 26, as well as with a threaded portion 29. A nut 30 which is secured against removal in any suitable manner secures the support to the shaft.

The car, which is circular in shape, consists of a closed lower part 31 and an upper wire mesh covered part 32. A door 33 gives access to the interior where a circular seat 34 and a back rest 35 are provided as shown. The roof 36 is provided with an opening through which the shaft 19 passes.

An annular guide 37 is attached to the roof 36 by a plurality of brackets 38 and engages on its inner surface with rollers 39 and 40, which turn horizontally in brackets 41 and 42 secured to the cross-member 17.

In Fig. 7, the guide ring and rollers are shown on a larger scale. The rollers are formed with flanges 43 which extend under the guide ring and act as guards should the car for any reason be dislodged from the vertical shaft.

It will be readily seen that, as the Ferris wheel turns, the gear 21 will drive the gear 20 and thus revolve the car 22 and that the rollers 39 and 40, on the guide ring 37, will steady the top of the car as it revolves.

In Figs. 3 and 6, the car is shown as applied to a merry-go-round and a modified form of guide is shown. In this case, the gear 21 is attached to the shaft 44, which is revolved in the manner common to overhead shafts on merry-go-rounds. The guide 45, which is plainly shown in Fig. 6, is provided with a plurality of cam faces 46, 47, and 48 on which the two rollers 39 and 40 engage. The shape of these cam faces are such that a wobbly motion is imparted to the top of the car, the effect of which is very thrilling. In this case, a sufficiently large hole 49 is cut in the roof 36. It will, of course, be understood that a guide of this kind might also be used in connection with a Ferris wheel and that a number of variations might be made in the number and shape of the cam faces.

Having thus described my invention, what I claim as new and wish to protect by Letters Patent is—

1. In combination with an amusement ride having a horizontal car-supporting shaft; a passenger car having a yoke rotatably mounted on the horizontal shaft, a vertical shaft rotatably mounted in the yoke, a car body fixed to the vertical shaft, transmission

means between the horizontal and vertical shafts for imparting rotary motion to the car body, a guide plate secured to the top of the car body, and rollers mounted on the yoke for engaging the guide plate and guiding the top of the car body during its rotation.

2. In combination with an amusement ride having a horizontal car-supporting shaft; a 10 passenger car having a yoke rotatably mounted on the horizontal shaft, a vertical shaft rotatably mounted in the yoke, a car body fixed to the vertical shaft, transmission means between the horizontal and vertical shafts for imparting rotary motion to the car body, a guide plate secured to the top of the car body, and rollers mounted on the yoke for engaging the guide plate and imparting a wobbly motion to the top of the 20 car body during its rotation.

3. In combination with an amusement ride having a horizontal car-supporting shaft; a passenger car having a yoke rotatably mounted on the horizontal shaft, a vertical shaft rotatably mounted in the yoke, a car body fixed to the vertical shaft, transmission means between the horizontal and vertical shafts for imparting rotary motion to the

car body, a guide plate secured to the top of the car body near its periphery, rollers 30 mounted on the yoke and engaging the guide plate for guiding the top of the car body during its rotation, and flanges on the rollers adapted to engage the underside of the guide plate and suspend the car body in case 35 of accidental dislodgement from the vertical shaft.

4. In combination with an amusement ride having a horizontal car-supporting shaft; a passenger car having a yoke rotatably 40 mounted on the horizontal shaft, a vertical shaft rotatably mounted in the yoke, a car body fixed to the vertical shaft, transmission means between the horizontal and vertical shafts for imparting rotary motion to 45 the car body, a guide plate having cam faces secured to the top of the car body near its periphery, rollers mounted on the yoke and engaging the cam faces on the guide plate for imparting a wobbly motion to the top of the car body during its rotation, and flanges on the rollers adapted to engage the underside of the guide plate and suspend the car body in case of accidental displacement from the vertical shaft.

HALLIGAN JOHNSON.
